UNITED STATES PATENT OFFICE.

THOMAS H. BUTLER, OF BALTIMORE, MARYLAND.

ANCHOR-BAR FOR ICE CAKES.

SPECIFICATION forming part of Letters Patent No. 730,001, dated June 2, 1903.

Application filed June 23, 1902. Serial No. 112,773. (No model.)

To all whom it may concern:

Be it known that I, THOMAS H. BUTLER, a citizen of the United States, residing at Baltimore, in the State of Maryland, have invented certain new and useful Improvements in Anchor-Bars for Ice Cakes; and I do hereby declare the following to be a full, clear, and exact description of the invention, such as will enable others skilled in the art to which it appertains to make and use the same.

This invention relates to anchor-bars which are frozen into cakes of ice formed in ice-machines for the attachment of lifting-tackle.

This invention consists in the novel construction and combination of the parts hereinafter fully described and claimed which permit the anchor-bars to be removed from the ice before it is sawed up in the sawing-machine.

20 In the drawings, Figure 1 is a cross-section through a portion of a freezing-tank provided with anchor-bars according to this invention. Fig. 2 is a longitudinal section through the freezing-tank.

25 A is a freezing-tank of any approved construction, and B is a freezing-plate secured in the tank A and provided with coils b, through which refrigerated brine is circulated.

30 C represents thawing-off pipes for steam, arranged under the bottom c of the tank A.

The ice cakes D form on both sides of the plate B, and after they are formed steam or other hot fluid is admitted to the pipes b and

35 C to detach the cakes of ice. In order to lift the detached cakes of ice out of the freezing-tank, anchor-bars E are frozen into them.

Each anchor-bar is hollow or tubular and is closed at its bottom end and provided with a

40 plate e, which rests on the bottom c of the freezing-tank. The plate e engages positively with the ice, and as the bottom end of the tube is closed the water does not get into the anchor-bar and become frozen in it so as to

45 close it. The upper end portions of the anchor-bars are screw-threaded at f, and g is a distance-piece which couples each pair of anchor-bars to the freezing-plate B. Each distance-piece has a socket h at its middle part, which

50 is dropped over the upper part of the freezing-plate, and it has holes in its end portions which engage with the anchor-bars and hold them in their preferred positions. Nuts i

may be screwed on the upper end portions of the anchor-bars, if desired, while the cakes of ice are being formed. When the cakes of ice have been detached, the distance-pieces g are removed and a lifter k is screwed on the top portion of each anchor-bar. Each lifter has an eye or hook for engagement with any crane or other lifting device. The lifters k may be used in place of the nuts i, if desired, to hold the distance-pieces coupled to the anchor-bars. When a cake of ice is lifted out of the freezing-tank, it is laid in an inclined or a flat position on a suitable table, preferably the table of the circular saw which cuts the cake into blocks of suitable size. The lifter is removed and a small steam-pipe is thrust into the open end of the tubular anchor-bar. Steam is admitted from a suitable boiler through the steam-pipe until the ice close to the anchor-bar is thawed and the anchor-bar is loose. The anchor-bar is then pulled out from the original bottom end of the cake of ice, and the cake is ready for the saw after all the anchor-bars have been removed.

What I claim is—

1. The combination, with a freezing-tank, of a tubular anchor-bar provided with a stopper which closes its lower end and which rests on the bottom of the tank, and a distance-piece which couples the upper end portion of the said bar to the said tank, substantially as set forth.

2. The combination, with a freezing-tank, of a tubular anchor-bar closed at one end, and a distance-piece which couples the other end portion of the said bar to the said tank, substantially as set forth.

3. The combination, with a freezing-tank, and a freezing-plate therein; of two tubular anchor-bars closed at their lower ends and arranged one on each side of the said freezing-plate, and a distance-piece which engages with the upper end portions of the said anchor-bars and has a socket at its middle part which engages with the said freezing-plate, substantially as set forth.

In testimony whereof I affix my signature in presence of two witnesses.

THOMAS H. BUTLER.
